FILM-FIRE-PROTECTION DEVICE FOR MOVING-PICTURE FILMS.

1,111,767.

Specification of Letters Patent. Patented Sept. 29, 1914.

Application filed October 14, 1912. Serial No. 726,147.

To all whom it may concern:

Be it known that I, DELBERT O. SEAMAN, a citizen of the United States, residing at Des Moines, county of Polk, and State of Iowa, have invented a certain new and useful Film-Fire-Protection Device for Moving-Picture Films, of which the following is a specification.

The object of my invention is to provide

- 10 a fire protection device for moving picture films which is of simple and inexpensive construction and can be readily and easily placed as an attachment on any of the standard moving picture machines.
- 15 A further object is to provide such a device comprising mechanism so constructed and arranged that should the film break at any point in its passage through the machine or should the top feed sprocket or the
- 20 take up feed sprocket fail to operate properly, or to carry the film past the light aperture in the film travel of the machine, the fire shutter will be automatically permitted to drop to closed position thereby
- 25 protecting the film against heat.

- A further object is to provide in such a device mechanism whereby in a motor driven picture machine the fire shutter will be permitted to drop to its closed position
- 30 whenever the film is broken in the machine or whenever it fails to travel properly over any of the sprockets and whereby a switch will be automatically operated to shut off the power from the motor and to acuate an
- 35 alarm which may be an audible or visible one.

My invention consists in certain details in the construction, arrangement and combination of the various parts of the device, 40 whereby the objects contemplated are attained, as hereinafter more fully set forth, pointed out in my claims, and illustrated in the accompanying drawings, in which—

Figure 1 shows a vertical, longitudinal, 45 sectional view through a moving picture machine equipped with my improved fire protection device. Fig. 2 shows a detail view of part of the actuating levers. Fig. 3 shows a side elevation of a portion of the 50 machine. Fig. 4 shows a rear elevation of a portion of the machine. Figs. 5 and 6 show detail views of a portion of the shutter and the shaft on which the same is mounted, and Fig. 7 shows a sectional, detail view of 55 the mechanism shown in Figs. 5 and 6.

In the accompanying drawings, I have used the reference numeral 10 to indicate generally the frame of a moving picture machine which may be of any suitable construction. Practically all of the standard 60 machines of this character are provided with mechanism for carrying a moving picture film past an opening through which the light is thrown.

Machines of this class have a top feed 65 sprocket 11 and a take up feed sprocket 12, and an intermittent sprocket 13 which I shall hereinafter more specifically refer to. The film 14 from a reel may be passed under an idler roller 15 and over the sprocket 11, 70 then under an adjustable roller 16 which may be moved closer to, or farther from the film and the sprocket 11 by means of a small lever 17. The film is usually fed through the machine in such a way that a 75 loop or slack portion 18 is left between the feed sprocket and the intermittent sprocket. The slack portion 18 is shown in Fig. 1 just after the film has left the feeder sprocket. The film passes downwardly over 80 a roller 19 and past the opening 20 over the intermittent sprocket 13. The film is held against the intermittent sprocket 13 by means of a roller 21.

It is customary in moving picture machines to leave a slack loop or portion 22 in the film between the intermittent sprocket 13 and the take up feed sprocket 12. In the drawings, I have shown the film extended downwardly from the intermittent sprocket 90 13 under and to position somewhat below the roller 23, then upwardly over the take up feed sprocket 12. The film is held against the take up feed sprocket 12 by means of a roller 24 mounted on an adjustable bracket 25 which is controlled by a lever 26. In this connection, it may be noted that standard films are provided along each edge with a series of perforations and that the sprockets hereinbefore referred to are 95 really comprised of rollers having at their outer ends teeth which engage said perforations and carry the film along.

It will be understood that moving picture machines are provided with mechanism not herein described and forming no part of my present invention whereby the sprockets 11 and 12 are steadily revolved, and whereby the sprocket 13 is intermittently revolved to bring each photograph of the film before 100 110

the opening 20, and to permit it to remain there for an instant. It will be seen that the loops 18 and 22 are necessary on account of the intermittent motion of the sprocket 13.

5 In the front of the opening 20 is an opening 27 in a plate 28. In front of the plate 28 is a plate 29 having the light aperture 30 therein, which opening 30 registers with the openings 27 and 20. Extending transversely 10 across the machine above the opening 30 is a shaft 31 on which the fire shutter 32 is mounted in the following manner: The shutter 32 has at its upper end a cylinder 33 rotatably mounted on the shaft 31. The shaft 15 31 is provided with a longitudinal central opening 34 in which is slidably mounted a cylinder 35. A longitudinal slot 36 communicates with the opening 34 and extends to the outer surface of the shaft 31. The slot 36 is considerably shorter than the opening 34. Mounted in the opening 34 between one end of said opening and one end of the cylinder 35 is an expansible coil spring 37 designed to hold the cylinder 35 at the outer 20 limit of its movement. Extending outwardly from the cylinder 35 is a pin 38 which slides in the slot 36 with every movement of the cylinder 35. The shutter cylinder 33 is provided with a longitudinal slot 25 39 which, in one position of the movement of the shutter 32 with relation to the shaft 31, registers with the slot 36 in the shaft 31. At one end of the slot 39 is an offset portion 40.

It will be seen that when the pin 38 is received in the slots 36 and 39 any rotation of the shaft 31 will cause movement of the shutter 32. On one end of the shaft 31 is an arm 41 of ordinary construction such as is found on standard moving picture machines. Said 35 machines are also provided with mechanism which I have indicated generally by the reference numeral 42 whereby the arm 41 is moved whenever the machine is placed in operation to raise the shutter 32. For causing the arm 41 to return to its normal position which is below the shaft 31 whenever the mechanism 42 ceases to operate upon said arm 41, I have mounted upon the shaft 31 and secured to a suitable part of machinery adjacent thereto a coil spring 45. With the ordinary machines the shutter 32 is held in its raised position as soon as the machine is in operation.

It is the purpose of my invention, as hereinbefore set forth to furnish mechanism in addition to that ordinarily employed on a machine of this class, whereby the shutter 32 may be acted upon to permit it to drop over the light aperture upon the happening of certain contingencies in connection with the film.

The rotary movement of the cylinder 33 on the shaft 31 is limited by the pin 38 in its movement in the slot 39 and the extension 40.

65 My improved mechanism for permitting

the shutter 32 to drop to vertical position from raised position whenever there is a break in the film or the film fails to travel properly through the machine is described as follows: The sprocket 11 is mounted on a 70 shaft 46. Mounted on the shaft 46 is an arm 47 in which the shaft 46 rotates freely. The arm 47 extends in opposite directions from the shaft 46 in substantially a horizontal position. On one end of the arm 47 75 which I will call its forward end, is a roller 48 over which the film 14 travels after it leaves the sprocket 11. It will be seen that if the slack portion 18 of the film is tightened the forward portion of the arm 47 will 80 be drawn downwardly and the rearward portion of said arm will be moved upwardly.

Suitably mounted on the frame of the machine at a point below the level of the shaft 46 is a stud screw 49 having forwardly and 85 rearwardly extending arms 50 and 51 mounted thereon. Pivoted to the rearwardly extending portion of the arm 47 is a downwardly extending link 52, the lower end of which is pivoted to the arm 50 at a 90 point in front of the stud 49. The arm 50 is held at the downward position of its movement by means of a weight 52 dependent therefrom. A transverse rock shaft 53 is mounted in front of the shaft 49. Fixed on the shaft 53 is the rearwardly extending arm 95 54, the rear end of which rests just above the forward end of the arm 50, as shown in Fig. 1 when the parts are in their normal positions. The arm 54 is provided with a 100 forwardly extending portion 55 and a downwardly and rearwardly extending portion 56 of approximately the same length. The outer ends of the portions 55 and 56 are connected by a curved plate 44, on one edge of which is a curved laterally extending flange 43, the edge of which is beveled or inclined, as shown in Figs. 4 and 6. When the arm 41 is raised, thereby rotating the shaft 31 and raising the shutter 32, the pin 38 stands in substantially vertical position and when the film is traveling properly the narrowest part of the flange 43 is adjacent to the pin 38. It will readily be seen that if the arm 54 is raised the wider part of the flange 43 will 105 engage the pin 38 and slide the same longitudinally in the slots 36 and 39 until the pin enters the extension 40. The pin will no longer support the shutter 32 which will drop by a force of gravity to the position shown by the dotted lines in Fig. 1, thereby covering the opening 30 and protecting the film against the light and heat which travel on the lines of the horizontal dotted lines in Fig. 1.

110 Mounted on the frame of the machine, preferably below the sprocket 12, is a stud 57 on which is pivotally mounted a downwardly and forwardly extending arm 58 on 115 the end of which is a roller 59 which stands

adjacent to the path of the film 14 when the parts are in normal position. Fixed to the upper end of the arm 58 is a rearwardly extending arm 60 which supports a weight 61, whereby the arm 58 is normally held at the forward position of its movement. The arm 58 is held in position by the film 14 when the latter is passing through the machine, as clearly shown in Fig. 1, at a point between the take-up feed sprocket 12 and the fire protection rollers 62. Pivoted to the shaft on which the roller 59 is mounted is a rearwardly extending arm 63 which is slidably mounted in a block 64 and is capable of slight tilting movement therein. Should the film break or pass entirely out of the machine, thereby permitting the arm 58 to move forwardly, then the rod 63 will stand in the path of the film and it will be necessary to move the arm 58 rearwardly to its proper position before another film is passed through the machine.

Pivoted to the stud 57 is a rearwardly extending arm 65. A link 66 is pivotally connected at its upper end to the rear end of the arm 51 and at its lower end to the arm 65. Formed on the arm 65 is a substantially vertical slot 67 in which travels a pin 68 extending laterally from the arm 60. The parts just described are so constructed that if the arm 65 tips downwardly the pin 68 will travel in the slot 67 and will not move the arm 60. On the other hand if the arm 58 should move forward a considerable distance the pin 68 reaches the limit of its movement in the slot 67 and moves the arm 65. On a stud 69 is a rearwardly extending arm 70 having a downward and forward extension 71 on which is the roller 23 hereinbefore mentioned which is encircled by the slack portion or loop 22 of the film. On the rear end of the arm 70 is a short lateral extension 72 which normally rests just above the arm 65.

The operation of the mechanism hereinbefore described, as far as it affects the closing of the shutter will now be more particularly illustrated: Assuming the machine to be in operation and the film to be passing through the machine in the proper manner, the shutter 32 will be held in its raised position by the pin 38. If for any reason the film 14 should be broken in two one end of it will pass between the fire protection rollers 62 and into the magazine. The instant the rearward pressure of the film 14 on the roller 59 mounted on the arm 58 is released, the weight 61 will drop downwardly carrying with it the arm 60 and thereby moving the arm 58 forwardly and upwardly past the path of film travel to position where the rod 63 stands in said path. As the arm 60 drops downwardly the pin 68 engages the lower edge of the slot 67 thereby drawing the arm 65 down-

wardly. Through the link 66 the arm 51 is moved downwardly thereby raising the arm 50 and the arm 54 and moving the wider portion of the flange 43 into contact with the pin 38. The pin 38 is moved to the extension 40 of the slot 39 permitting the shutter 32 to drop to closed position. Assuming that the intermittent sprocket 13 fails to act properly, as for instance, for the reason that the perforations in the film are torn out so that the film is not properly engaged by the teeth on the sprocket 13, then the sprocket 12 will take up the slack portion 22 causing the film to engage and raise upwardly the roller 23. The extension 72 on the arm 70 will engage the arm 65 and force the same downwardly, thereby putting in operation the mechanism whereby the shutter is moved to closed position. Assuming that the difficulty is that the sprocket 11 fails to properly convey the film then the intermittent sprocket will take up the slack portion 18 and the film will engage the roller 48 lowering the arm 47, raising the link 52 and through the arms 50, 54, 55 and 56, the curved plate 44 and the flange 43, sliding the pin 38 to position where it permits the shutter to drop.

It will be seen that my improved device is effective where the picture machine is operated by a motor, by hand power or from any other source of energy.

I have provided additional mechanism for machines operated from a motor whereby the motor is shut off and an alarm is actuated when any of the contingencies mentioned above arise.

In Fig. 1, I have shown the motor 75 included in an electric circuit in which the current is originated in the batteries 76. I have shown also a two-way switch having the movable switch member 77 which may be moved to engagement with either of the contact points 78 or 79. I have provided a third wire connected with one of the wires of the circuit and with the contact point 79. The other wires are connected respectively with the switch member 77 and with the contact point 78. Pivoted to the rear end of the arm 65 is a downwardly extending link 80 which is pivoted at its lower end to one arm of a bell crank lever 81. The other arm of the lever 81 is pivoted to a link 82 which is secured to the movable switch member 77 by means of insulating material 83.

The parts just described are so arranged that when the arm 65 is in its normal position the switch member 77 engages the contact point 78 and the current from the batteries passes through the motor whereby the machine is operated. When the arm 65 drops downwardly upon the happening of any of the contingencies hereinbefore mentioned the switch member 77 is moved by

means of the link 80, the lever 81 and the link 82 to position in engagement with the contact point 79. The current through the motor is then broken and a circuit is established through an alarm 84 which may be visible or audible as desired.

The advantages of my improved device may be seen from the foregoing description. With the moving picture projecting machines now in use, whenever the film is stopped, even for a brief interval of time longer than the instant necessary for properly showing the picture, there is danger that heat passing through the aperture 30 10 will set the film which is ordinarily made of celluloid or similar composition afire. Such fires frequently happen in the use of moving picture machines. The roller 48 also prevents the teeth on the sprocket 11 15 from drawing the film 14 below and around said sprocket, thereby avoiding interruption in the travel of the film.

It will be seen that with my machine, whenever the film fails to travel properly 20 through the machine it automatically actuates mechanism whereby the shutter 32 is permitted to drop to its closed position. In a motor driven machine the motor is shut off automatically at the same time and 25 a suitable alarm is actuated.

In the following claims when I use the term intermittent sprocket, I mean to include any suitable means for feeding the film across the light opening in such a manner as to hold each picture motionless for 30 an instant's exposure.

I claim as my invention:

1. In a moving picture machine of the type having a top feed sprocket and an intermittent feed sprocket, a shutter hinged at its upper edge, means for holding said shutter in its open position, a lever pivoted between its ends, one end of said lever being designed to stand normally in the path of 40 a slack loop in a film between said sprockets, a link pivoted to the other end of said lever, a second lever pivotally mounted with one end adjacent to and in operative relation with said shutter holding means for moving 45 the same to an operative position when said second lever is moved to one position of its movement, said link being pivoted to said second lever so that should said slack loop become taut the end of said first lever within 50 the loop will be engaged and lowered and the second lever will thereby be moved and will engage said first means for moving it to said inoperative position.

2. In a moving picture machine of the type having a top feed sprocket and an intermittent feed sprocket, a shutter hinged at its upper edge, means for holding said shutter in its open position, a lever pivoted between its ends, having one end arranged to 60 be within the slack portion of a film between

said sprockets, a second lever having one end adjacent to and in operative relation with said shutter holding means for moving the same to inoperative position when said second lever is moved to one position of its 70 movement, a link pivoted to the other end of said first lever and to said second lever so that when the slack portion of the film becomes taut the end of the first lever within said slack portion is moved and said second 75 lever is thereby moved to position for moving the shutter holding means to inoperative position, an electric circuit for furnishing power to operate the machine, a switch therein, mechanism for connecting said second lever with said switch so that when said second lever is moved to its last described position the switch is moved to position for breaking the circuit.

3. In a moving picture machine of the type having intermittent and take-up feed sprockets, a hinged shutter, means for holding said shutter in open position, a lever pivoted between its ends, an arm on said lever arranged to be within a slack loop 90 portion of a film between said sprockets, a second lever pivoted between its ends with one end adjacent to and in operative relation with said shutter holding mechanism, a link connecting said levers so that when said slack portion becomes taut, said first lever will move said link, thereby moving the second lever to position for engaging said shutter holding means and moving it to inoperative position.

4. In a moving picture machine, a hinged shutter, means for holding said hinged shutter open, a lever pivoted between its ends with one end adjacent to and in operative relation with a shutter holding means, a link pivoted to the other end of said lever, means for holding a portion of a film taut in the machine, a bell crank lever having one arm arranged to be engaged by said taut portion of the film for holding the lever in one position of its movement, means operatively connected with said lever for normally throwing said arm across the path of travel of the film should the tension of the film be released, means for operatively connecting said link with the other arm of said bell crank lever, so that should the tension on the film be removed, one arm of said bell crank lever is thrown into the path of the film, the other arm moves said last named means and said link for moving said first named lever to position for engaging said shutter holding means and moving it to inoperative position.

5. In a moving picture machine, a hinged shutter, means for holding the same in open position, means for holding a portion of a film taut in the machine, a lever designed to be engaged by said taut portion, means for normally moving said lever to a position ex- 125 130

tending across the path of travel of said taut portion, means for operatively connecting said lever with said shutter holding means so that if the taut portion should become slack or the film break, said shutter holding means will be released and said lever moved to its position extending cross the path of film travel.

6. In a moving picture machine, a hinged shutter, means for holding said shutter in open position, a lever pivotally mounted on the frame of the machine, a lever pivoted between its ends on the frame of the machine having an arm on one end arranged 10 to be within a slack portion of a film threaded through the machine, and an arm on the other end located just above the first lever, a link pivoted to the first lever and to the last described arm of the second lever so that when the slack portion of the loop becomes taut and moves said first arm, said second arm engages and moves said first lever, an electric circuit for operating the machine, a switch therein, means for operatively connecting said first lever with 15 said shutter holding means for moving the latter to inoperative position when said first lever is moved by said second arm, and means for operatively connecting the first 20 lever with the switch.

7. In a moving picture machine, means for holding a portion of film taut in the machine, a support, a bell crank lever mounted thereon having one arm designed to be engaged by the taut portion of the film, means whereby the other arm of said lever is moved when the tension on said taut portion is released, a second lever pivoted to said first support, a second support, a third lever pivoted thereto between its ends, an arm on one end of said lever, received within the slack portion of said film, a lateral extension on the other arm of the third lever resting on the second lever, a slot formed on the 25 second lever, and a pin on the second arm of said first lever traveling in said slot.

8. In a moving picture machine having intermittent and take-up feed sprockets, means for holding a portion of a film taut 30 in the machine, a support, a bell crank lever mounted thereon having on one arm a spindle on which is a roller designed to be engaged by said taut portion of the film, a rod pivoted to said spindle, means operatively connected with the other arm, so arranged that if the tension on said taut portion should be released, the first named arm of said bell crank lever would move to extend said rod across the path of the film 35 40 and prevent the rethreading thereof until said bell crank lever should be returned to its first position, a second lever pivoted to said support, a second support, a second

bell crank lever pivoted thereto between its ends, an arm on one end of said second bell crank lever, arranged to be received within a slack portion of said film, means whereby the movement of said second bell crank lever moves said second lever, a slot formed on the second lever, a pin on the second arm of said first lever traveling in said slot, a hinged shutter, means for holding the said shutter open, a lever pivoted between its ends, arranged with one arm adjacent to said shutter holding means, and a link connecting said second lever with the other arm of said last lever, so arranged that the movement of said last lever releases said shutter holding means.

9. In a moving picture machine of the type having a top feed sprocket and an intermittent feed sprocket, a shutter hinged at its upper edge, means for holding said shutter in its open position, a lever pivoted between its ends, one end of said lever being 80 designed to stand normally in the path of a slack loop in a film between said sprockets, a link pivoted to the other end of said lever, a second lever pivotally mounted with one end adjacent and in operative relation with 85 said shutter holding means for moving the same to inoperative position when said second lever is moved to one position of its movement, said link being pivoted to said second lever so that should said slack loop 90 become taut the end of said first lever within the loop will be engaged and lowered and the second lever will thereby be moved and will engage said first means for moving it to said inoperative position, an electric circuit, including a switch, a signal, and means for operatively connecting the switch with 95 one of said levers for throwing the switch when the lever is moved.

10. In a moving picture machine, a hinged shutter, means for holding the same in open position, means for holding a portion of a film taut in the machine, a lever designed to be engaged by said taut portion, means for normally moving said lever to a position extending across the path of travel of said taut portion, means for operatively connecting said lever with said shutter holding means so that if the taut portion should become slack or the film break, said shutter holding means will be released and said lever moved to its position extending across the path of film travel, an electric circuit including a switch, and means for connecting said lever with said switch for throwing 100 the switch when the lever is moved.

Des Moines, Iowa, Oct. 7, 1912.
DELBERT O. SEAMAN.
